(57) **CLAIM**

The ornamental design for a mobile 3D viewer, substantially as shown and described.

DESCRIPTION

FIG. 1 is a perspective view of a mobile 3D viewer, showing our new design;

FIG. 2 is a front elevational view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a front elevational view in a folded state of the mobile 3D viewer;

FIG. 9 is a top plan view in a folded state of the mobile 3D viewer;

FIG. 10 is a right side view in a folded state of the mobile 3D viewer;

FIG. 11 is a splayed view of the mobile 3D viewer.

FIG. 12 is a cross sectional view of FIG. 2 taken along line 12-12; and,

FIG. 13 is a cross sectional view of FIG. 8 taken along line 13-13.

1 Claim, 13 Drawing Sheets
